UNITED STATES PATENT OFFICE

OTTO R. FANDREY, OF TOLEDO, OHIO

DESIGN FOR A TABLE LAMP

Application filed June 19, 1931. Serial No. 40,273. Term of patent 3½ years.

To all whom it may concern:

Be it known that I, OTTO R. FANDREY, a citizen of the United States, residing at 1330 Page Street, Toledo, in the county of Lucas and State of Ohio, have invented a new, original, and ornamental Design for Table Lamps, of which the following is a specification, reference being had to the accompanying drawings, forming part thereof.

Fig. 1 illustrates a face view of the lamp showing my new design. Fig. 2 illustrates a top view of the lamp.

The part 1 is formed of translucent blue-green glass, the lower end portion 2 covered with a deep blue opaque paint producing, by the aid of the lamp bulb 3, when lighted, a moonlight effect.

I claim:

The ornamental design for a table lamp as shown and described.

In witness whereof I have hereunto signed my name to this specification.

OTTO R. FANDREY.
